UNITED STATES PATENT OFFICE.

MORRIS FORLANDER, OF NEW YORK, N. Y.

LOCK.

1,398,636.

Specification of Letters Patent.

Patented Nov. 29, 1921.

Application filed January 25, 1921. Serial No. 439,740.

To all whom it may concern:

Be it known that I, MORRIS FORLANDER, a citizen of Russia, residing at New York, in the county and State of New York, have invented certain new and useful Improvements in Locks, of which the following is a full, clear, and exact specification.

This invention relates to locks, and has for its object to provide a jimmy-proof lock having a plurality of bolts of different types, thereby increasing the security of the fastening.

The invention contemplates the provision of swinging hook-shaped bolts on the keeper of a lock, said bolts being actuated by a sliding bolt in the lock casing when said sliding bolt is projected into the keeper. The hook-shaped bolts are adapted to interlock with the casing of the sliding bolt, thus forming a double acting lock and keeper in which the sliding and swinging bolts are combined. The arrangement of the bolts is such that a burglar cannot saw through them or jimmy the lock.

A further object of the invention is to facilitate the operation of the hook-shaped bolts by the sliding bolt by giving the latter a step by step movement in projecting and retracting the same. Another object is to adapt the sliding bolt to be actuated by separate roll backs arranged out of alinement with each other and controlled by different key locks arranged on opposite sides of the door. A further object is to increase the security of the lock by having the casing for the sliding bolt overlap and interlock with the casing for the swinging bolts. Other objects will appear as the description proceeds.

The invention will be first hereinafter described in connection with the accompanying drawings which constitute part of the specification, and then more specifically defined in the claims at the end of the description.

In the accompanying drawings, wherein similar reference characters are used to designate corresponding parts throughout the several views:

Figure 1 is a front elevation of a lock constructed substantially in accordance with this invention and applied to a door and jamb.

Fig. 2 is a horizontal section on the line II—II of Fig. 1.

Figs. 3, 4 and 5 are sectional views taken on the line III—III of Fig. 2 and showing

different positions of the sliding and swinging bolts and the mechanism for reciprocating said sliding bolt.

Fig. 6 is a detailed perspective view of the sliding bolt.

Fig. 7 is a detailed perspective view of the tumbler, and

Fig. 8 is a top plan view of the lock and keeper applied to the door and jamb, the latter being shown in section.

In the drawings, 1 designates a portion of a door and 2 a part of the jamb therefor. The casing 3 for the sliding bolt 4 has an angularly extending flange 5 secured to the edge of the door by screws 6 which are concealed when the door is shut. Said casing 3 may also be fastened to the face of the door by screws 7, but it will be understood that the screws 6 will hold the casing in position even though the screws 7 are removed.

The keeper 8, which also constitutes the casing for the swinging bolts 9, also has an angularly extending flange secured to the edge of the chamber by screws 11 which are also concealed when the door is shut. The keeper 8 may also be secured to the face of the chamber by screws 12, but these screws are not necessary to fasten said keeper in place. It will be seen that the screws 6 and 11, which are passed through the flanges 5 and 10, cannot be removed when the door is locked, so that it is impossible for a burglar to open the door when locked by bodily removing either the lock or keeper.

The swinging bolts 9 are hook-shaped, as shown, and normally extend in opposite directions from their pivots 13. The inner pivoted ends of said swinging bolts have projecting lugs 14 which extend into the path of the sliding bolt 4 and are adapted to be engaged by the latter as it is projected for swinging the bolts 9 out of the keeper and into engagement with slots 15 in the upper and lower edges of the casing 5. When released, the swinging bolts 9 are retracted into the keeper or casing 8 by springs 16 connected to a pin 17 in said keeper and to the bolts 9 at 18.

The sliding bolt 4 has a shank 19 provided with a horizontal slot 20 into which a fixed lug 21 in the casing 3 projects for guiding the bolt in its reciprocations and limiting its movement in each direction. A lug 22 projects from the side of the shank 19 into a slot 23 in a tumbler 24 which is pivoted to a fixed pin 25 in the casing 3 and yieldingly

pressed upward by a leaf spring 26. The slot 23 in the tumbler has a pair of lugs 27 and 28 adapted to interlock with the lug 22 on the shank of the sliding bolt to prevent the latter from being moved except when said tumbler is swung downwardly, as shown in Fig. 4, to move said lugs 27 and 28 out of the path of the lug 22. As shown in Figs. 3 and 5, the tumbler 24 normally extends in substantially horizontal position with its upper edge practically flush with the upper edge of the shank 19. In said upper edge of the shank 19 there are formed four notches, two of which 29 extend only part way through said shank, while the other two notches 30 extend entirely through the shank.

The sliding bolt is adapted to be actuated by either one of two roll backs 31 and 32 which are controlled by different key-actuated cylinder locks 33 and 34. The cylinder lock 33 is mounted on the front of the casing 3 to be actuated from the inside of the door, while the cylinder lock 34 is mounted in the body of the door so as to be accessible from the outside thereof, said lock 34 being connected to the roll back 32, which is swiveled on the back plate 35 of the lock casing 3, by a connecting piece 36, best shown in Fig. 2. The roll backs 31 and 32 are arranged out of alinement with each other, the tooth 37 of the roll back 31 being adapted to engage in the notches 29 of the shank of the bolt 4, while the tooth 38 of the roll back 32 is adapted to engage in the notches 30 in said shank. As shown in Fig. 2, the tooth 38 is wider than the notches 29 so that it will not enter them but will only be operatively engaged with the notches 30.

To facilitate the operation of the swinging bolts 9 by the projection of the sliding bolt 4, it has been found advantageous to provide for a step by step movement of said sliding bolt rather than to fully project it in one movement. For this reason, two of the notches 29 are provided to be engaged by the tooth 37 of the roll back 31, and two of the notches 30 are also provided for engagement by the tooth 38 of the roll back 32, so that it requires two revolutions of either of said roll backs to fully project or retract the bolt 4. It will be noted that as the tooth of either of the roll backs is inserted into the corresponding notches in the shank of the sliding bolt, said tooth will engage the upper edge of the tumbler 24 and depress the latter so as to permit the lug 22 on said shank to pass over first one and then the other of the lugs 27 and 28. Fig. 3 shows the unlocked position of the sliding and swinging bolts, the locked position of said bolts being indicated in dotted lines. Fig. 4 shows the positions of the parts when the tooth 37 of the roll back 31 is engaged with the first one of the notches 29, in which

position it has depressed the tumbler 24 so as to release the bolt 4 and has partially projected said bolt. Fig. 5 illustrates the positions of the parts at the end of one full revolution of the roll back 31. A further revolution of said roll back will cause its tooth 37 to engage the second notch 29 in the shank of the bolt 4 in the same manner as it engages the first notch, Fig. 4, thereby fully projecting said bolt to the position illustrated in dotted lines in Fig. 3. The actuation of the bolt 4 by the roll back 32, controlled from the other side of the door, is the same as just described in connection with the roll back 31 except that said roll back 32 engages the notches 30 instead of the notches 29 in the shank of said bolt.

The slots 15 in the upper and lower edges of the casing 3 are preferably guarded by projections 39 on the front of said casing. Projecting lugs 40 are preferably formed on the front of the keeper 8 to engage in openings 41 in an extension 42 of the front plate of the casing 3 when the door is shut, thereby further increasing the security of the fastening.

I claim:

1. The combination with a lock, of a keeper, a bolt operatively mounted in the lock, and a pair of swinging bolts mounted in the keeper and adapted to engage opposite edges of the lock.

2. The combination with a lock having slots in its upper and lower edges, of a keeper, a bolt operatively mounted in the lock to engage the keeper, and a pair of swinging bolts mounted in the keeper and adapted to engage said slots in the lock.

3. The combination with a lock having a slot therein, of a keeper, a bolt operatively mounted in the lock to engage the keeper, and a swinging hook-shaped bolt wholly within the keeper and adapted to be projected into engagement with the slot in the lock, the free end of said bolt being substantially parallel to the end plate of the lock when swung into engagement with said slot and serving to bind the keeper and lock together.

4. The combination with a lock, of a keeper, a sliding bolt operatively mounted in the lock to be projected into the keeper, a pair of swinging bolts pivoted in the keeper and extending in opposite directions, lugs on said swinging bolts extending into the path of the sliding bolt whereby said swinging bolts will be projected into engagement with the lock when said sliding bolt is projected into the keeper, and means for retracting said swinging bolts into the keeper when the sliding bolt is retracted into the lock.

5. The combination with a lock having a horizontal face provided with a slot, of a keeper, a bolt operatively mounted in the

lock to engage the keeper, a hook-shaped bolt pivoted in the keeper and adapted to be projected into engagement with said slot in the lock when the sliding bolt is projected, and a projection on said horizontal face of the lock in front of said slot for masking the latter.

6. The combination with a lock having slots in its upper and lower edges, of a keeper, a bolt operatively mounted in the lock to engage the keeper, a pair of oppositely extending hook-shaped bolts pivoted in the keeper and adapted to be projected into engagement with said slots in the lock 10 when the sliding bolt is projected into the keeper, and projections on the upper and lower edges of the lock in front of said slots for masking the latter.

7. The combination with a lock, of a keeper, a sliding bolt mounted in the lock and adapted to be projected into engagement with the keeper, a roll back in the lock, and means for effecting a step by step movement of the bolt by a plurality of revolutions 20 of said roll back.

8. The combination with a lock, of a keeper, a sliding bolt operatively mounted in the lock and adapted to be projected into engagement with the keeper, a swinging bolt 30 mounted in the keeper to be projected into engagement with the lock when said sliding bolt is projected into the keeper, a roll back in the lock, and means for effecting a step by step movement of the sliding bolt by 35 a plurality of revolutions of the roll back.

9. The combination with a lock, of a keeper, a sliding bolt operatively mounted in the lock and adapted to be projected into engagement with the keeper, there being a 40 plurality of notches in said bolt, and a roll back adapted to successively engage said notches during a plurality of revolutions for effecting a step by step movement of said bolt.

45 10. The combination with a lock, of a keeper, a sliding bolt operatively mounted in the lock and adapted to be projected into

engagement with the keeper, there being a plurality of notches in the bolt, and two roll backs to be actuated from opposite sides 50 of the lock and adapted to engage different notches in the bolt.

11. The combination with a lock, of a keeper, a sliding bolt operatively mounted in the lock and adapted to be projected 55 into engagement with the keeper, there being two series of notches in said bolt and two roll backs to be operated from opposite sides of the lock, each roll back being adapted to successively engage a plurality of 60 notches in a separate series for effecting a step by step movement of the bolt.

12. The combination with a lock, of a keeper, a sliding bolt operatively mounted in the lock and adapted to be projected into 65 engagement with the keeper, a pair of roll backs arranged out of line with one another in the lock and adapted to be operated from opposite sides of said lock, and means whereby either roll back may actuate the 70 lock independently of the other roll back.

13. The combination with a lock, of a keeper, a sliding bolt operatively mounted in the lock and adapted to be projected into engagement with the keeper, there being two 75 notches of different widths in said bolt, and two roll backs adapted to be operated from opposite sides of the lock, said roll backs being of different widths to correspond to the different widths of said notches, 80 whereby the wider roll back cannot enter the narrower notch.

14. The combination with a lock, of a keeper, a bolt operatively mounted in the lock to engage the keeper, and a pair of 85 hook-shaped bolts in the keeper to engage opposite edges of the lock, the free ends of said hook-shaped bolts being substantially vertical when swung into engagement with the lock and serving to bind said keeper 90 and lock together.

In testimony whereof I have signed my name to this specification.

MORRIS FORLANDER.
